US00D693681S

(12) United States Design Patent
Allen et al.

(10) Patent No.: US D693,681 S
(45) Date of Patent:  Nov. 19, 2013

(54) PACKAGE

(75) Inventors: Samantha R. Allen, Wilton, ME (US);
Elena Marie Angeles Schroeder,
Highwood, IL (US); Kartika Amber
Huston, Fort Wright, KY (US); Anne
Claire Gibble, Cincinnati, OH (US)

(73) Assignee: The Gillette Company, Boston, MA
(US)

() Term: 14 Years

(21) Appl. No.: 29/425,161

(22) Filed: Jun. 20, 2012

(51) LOC (9) Cl. 09-07

(52) U.S. Cl.

USPC D9/434

(57) CLAIM

The ornamental design for package, as shown and described.

DESCRIPTION

FIG. 1 is a front view of a package of the present invention;

FIG. 2 is a back view thereof;

FIG. 3 is a right side view thereof;

FIG. 4 is a left side view thereof;

FIG. 5 is a top view thereof; and,

FIG. 6 is a bottom view thereof.

The broken lines depict environmental subject matter only and form no part of the claimed design.
